UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed October 6, 1921. Serial No. 505,770.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

This invention relates to attachments for typewriting machines, and is designed for use where the items on a plurality of successive outer sheets, such as statement or memorandum sheets, are typed also upon an inner sheet, such as a journal or other record-sheet, which remains in the machine, together with its carbon-sheet, while the statement-sheets are changed. When a statement-sheet is to be inserted, the lower rearwardly-extending portions of the record-sheet and the carbon-sheet must be raised, and the statement-sheet inserted thereunder, so that said statement-sheet will be the outermost sheet at the front of the platen. To avoid the necessity of lifting the rearward portions of the carbon and record sheets each time a new statement-sheet is to be inserted, this invention provides an auxiliary paper-table mounted above the usual main paper-table, so that the record and carbon sheets may be fed over said auxiliary paper-table which holds the rearward portions of said sheets elevated, thus permitting the statement-sheets to be fed over said main table without necessitating the lifting of the rear ends of the carbon-sheet and record or ledger-sheet.

The lower edge of the auxiliary paper-table terminates some distance to the rear of the platen to provide sufficient clearance for sheets fed over said main table, and when the lower end of the record-sheet is being typed, said end would ordinarily drop off the auxiliary table. If the carbon-sheet were of the same length as the record-sheet, both sheets would drop off the table when the lower end of the record-sheet was being typed, and the rear portions of the sheets would interfere with the insertion of a new statement-sheet. To avoid this difficulty, the carbon-sheet is longer than the record-sheet, so that, when the lower end of the latter is being typed, the lower end of the carbon-sheet is still on the auxiliary table, thus permitting the statement-sheets to be inserted thereunder without interference.

The carbon-sheet and the record-sheet are passed over the auxiliary table when inserting them into the machine. The auxiliary table normally stands at an inconvenient angle for introducing the leading ends of the sheets between the rear feed-rolls and the platen. To obviate this objection, the auxiliary paper-table is pivotally mounted so that it may be thrown rearwardly to stand substantially at the same angle as the main paper-table when the carbon and record sheets are to be inserted around the platen. When the leading ends of the carbon and record sheets have been drawn around to the printing point, the auxiliary table may again be raised above the main table. Suitable stops may be provided for limiting the forward and rearward movement of the auxiliary table and devices for holding said table in forward or rearward position.

Other features and advantages will hereinafter appear.

In the accompanying drawings,

Figure 1 is a view of the typewriter carriage with the invention applied thereto.

Figure 2 is a sectional side elevation showing, in dot-and-dash lines, the position of the auxiliary table when a record-sheet is to be inserted.

Figure 3 is a view similar to Figure 2, but illustrating the insertion of a statement-sheet when the trailing end of the record-sheet has been fed off the lower end of the auxiliary table.

Referring to the drawings, there is shown a platen-frame 10 forming part of the usual carriage in the Underwood standard typewriting machine, said frame comprising end walls 11 in which is journaled a shaft 12 having a platen 13 fixed thereto, said platen being rotatable by knobs or finger-wheels 14 fixed to the ends of the platen-shaft and the usual line-spacing mechanism (not shown). The platen-frame supports a paper-table 18 terminating at the front in a paper-apron 19, the latter having openings through which extend the usual front and rear pressure rolls 20 and 21.

To maintain the rear portion of an inner record or proof-sheet 25 and of an outer carbon-sheet 26 raised above the paper-table 18, in order to permit several successive statement or memorandum sheets 27 to be inserted into the machine while the same

record-sheet and carbon-sheet remain in the machine and without interference by the rearward portions of said record and carbon sheets, said record-sheet and carbon-
sheet are passed over an auxiliary paper-table 30 raised above table 18 and positioned to direct sheets to the bite formed by the platen and the rear pressure rolls 21. With this arrangement, the rear portions of the carbon and record sheets are always held above the table 18, thus permitting the statement-sheets to be inserted beneath the carbon and record sheets without interference by the latter. When a statement-sheet has been typed, the pressure rolls 20 and 21 are thrown off by the usual feed-roll release mechanism (not shown) and the statement-sheet is withdrawn, the record and carbon-sheets, which are wider than the statement-sheet, being held by the usual paper-fingers 32. A new statement-sheet is passed over table 18 beneath the auxiliary table 30, and hence beneath the rearward portions of the record-sheet and the carbon-sheet and adjusted to the printing point indicated by the type-head 33. The pressure rolls are then again applied so that the sheets may be fed around the platen in the usual manner as they are typed.

This operation is repeated as often as desired, the record and carbon sheets being suitably line-spaced. When the bottom of the record-sheet is being typed, the lower end thereof has left the auxiliary table, since said table terminates some distance to the rear of the platen to allow sufficient clearance space for the statement-sheet. To enable the insertion of the statement-sheet under the lower end of the record-sheet without interference of the lower end of said record-sheet, the carbon-sheet is somewhat longer than the record-sheet, so that the carbon-sheet rests upon the auxiliary table even after the record-sheet has left said table (see Figure 3). Since the carbon-sheet is the outer sheet, the statement-sheets may be inserted thereunder while the bottom of the record-sheet is beneath the platen.

To insert the record and carbon sheets into the machine, they are passed over the auxiliary table and their leading ends fed into the bite between the platen and rear pressure rolls 21. The auxiliary table, however, normally stands at an angle which renders it convenient for the insertion of the statement-sheets and which renders it inconvenient for the leading ends of the record and carbon sheets to be passed into the bite of the platen and the feed-rolls 20. The auxiliary table is, therefore, pivotally mounted preferably on a tie-bar 40 upon which the usual paper-fingers 32 are mounted, so that said table may be swung rearwardly to an angle substantially the same as the main paper-table 18. After the leading ends of the record and carbon sheets have been inserted into the bite, the auxiliary table may be raised to its normal position. The auxiliary table may be held in its raised position by a spring catch or detent 43 engaging a tie-rod 44 mounted between brackets 45. The brackets 45 may be the usual tally-strip attachment rod brackets. The rearward movement of the auxiliary table may be limited by stop 46 on said catch 43 engaging said rod 44.

The statement-sheets 27 are narrower than the record-sheets 25, and, as shown in Figure 1, pass between the paper-fingers 32. To prevent the leading ends of the statement-sheets from falling forwardly, provision may be made of a finger 47 suitably supported on the typewriter carriage.

Variations may be resorted to within the scope of the invention, and portions of the improvements may be used without others.

Having thus described my invention, I claim:

1. In a typewriting machine, in combination, a revoluble platen, a platen-frame having a rear paper-table, and an auxiliary table above the rear paper-table and pivoted to swing about an axis adjacent the rear of the platen to a position close to the rear paper-table for the insertion of a work-sheet over the auxiliary table, and to a raised position for the insertion of a work-sheet around the platen outside of the work-sheet inserted over the auxiliary table.
2. In a typewriting machine, in combination, a revoluble platen, a platen-frame having a rear paper-table, an auxiliary table above the rear paper-table and pivoted to swing about an axis adjacent the rear of the platen to a position close to the rear paper-table for the insertion of a work-sheet over the auxiliary table, and to a raised position for the insertion of a work-sheet around the platen outside of the work-sheet inserted over the auxiliary table.
3. In a typewriting machine, in combination, a revoluble platen, a platen-frame comprising a rear paper-table, an auxiliary table above the rear paper-table, brackets extending upwardly from the auxiliary table near its lower edge, and means on said platen-frame for pivotally supporting the upper ends of said brackets to swing about an axis adjacent the rear of the platen.
4. In a typewriting machine, in combination, a revoluble platen, a platen-frame comprising a rear paper-table, an auxiliary table above the rear paper-table, brackets extending upwardly from the auxiliary table near its lower edge, means on said platen-frame for pivotally supporting the upper ends of said brackets to swing about

an axis adjacent the rear of the platen, and means for detaining said auxiliary table in its lower position close to the rear paper-table for the insertion of a work-sheet over 5 the auxiliary table, or in raised position for the insertion of a second work-sheet over the rear paper-table and around the platen outside of the first work-sheet.

5. In a typewriting machine, in combination, a revolute platen, a platen-frame comprising a rear paper-table and having a tie-rod extending thereacross behind the upper part of the platen, paper-fingers on said rod extending over the top of the platen and 10 down over the front thereof to engage the edges of a wide sheet on the platen, and an auxiliary table pivoted on said tie-rod for movement into position adjacent the rear paper-table to direct the wide sheet to the 15 bottom of the platen, and into an upper position to hold the wide sheet above the rear paper-table to permit the successive insertion 20 of narrow sheets between the wide sheet and the rear paper-table and between the 25 paper-fingers at the delivery side of the platen.

6. In a typewriting machine, in combination, a revolute platen, a platen-frame comprising a rear paper-table and having a tie-rod 30 extending thereacross behind the upper part of the platen, paper-fingers on said rod extending over the top of the platen and down over the front thereof to engage the edges of a wide sheet on the platen, an auxiliary table pivoted on said tie-rod for movement 35 into position adjacent the rear paper-table to direct the wide sheet to the bottom of the platen, and into an upper position to hold the wide sheet above the rear paper-table to permit the successive insertion 40 of narrow sheets between the wide sheet and the rear paper-table and between the paper-fingers at the delivery side of the platen, a traveling carriage in which said 45 platen-frame is mounted, and a paper-finger at the front of the carriage to engage the narrow sheets at the delivery side of the platen to keep them from falling forwardly away from the platen.

50 7. In a typewriting machine, in combination, a platen, a platen-frame in which said platen is journaled and comprising a rear paper-table, an auxiliary table having its lower edge adjacent the apex of the opening 55 between the rear paper-table and the platen, and means for mounting said auxiliary table on the platen-frame for movement of its rear edge to an upper position to hold work-sheets on the auxiliary table above the rear 60 paper-table to avoid interference with sheets inserted over the rear paper-table, or to a lower position for insertion of a work-sheet over the auxiliary table.

8. The combination with a platen-frame and a revolute platen mounted in said

frame, said frame comprising a main paper-table, of an auxiliary paper-table pivotally mounted on said platen-frame and positioned normally above said main table to hold the rearward portions of sheets passed 70 over said auxiliary table in raised position above said main table so as not to interfere with the feeding of sheets over said main table, said auxiliary table being swingable to lowered position so that the 75 sheets operating thereover may be more easily inserted around said platen, means for holding said auxiliary table in raised position, said means comprising a rod fixed to said platen-frame, a spring-catch 80 fixed to said auxiliary table and engaging said rod, and means for limiting the downward movement of said auxiliary table, said last-named means comprising a stop carried by said auxiliary table and engaging said 85 rod in the lowered position of the auxiliary table.

9. The combination with a platen-frame and a revolute platen mounted in said frame, said frame comprising a main paper-table, of an auxiliary paper-table pivotally mounted on said platen-frame and positioned normally above said main table to hold the rearward portions of sheets passed 90 over said auxiliary table in raised position above said main table so as not to interfere with the feeding of sheets over said main table, said auxiliary table being swingable to lowered position, so that the sheets operating thereover may be more easily inserted 95 around said platen, means for holding said auxiliary table in raised position, said means comprising a rod fixed to said platen-frame, a spring-catch fixed to said auxiliary table and engaging said rod, and means for limiting the downward movement of said auxiliary table, said last-named means comprising a stop carried by said spring-catch and engaging said rod in the lowered position of the auxiliary 100 table.

10. The combination with a platen-frame and a revolute platen mounted in said frame, said frame comprising a main paper-table, of an auxiliary paper-table pivotally mounted on said platen-frame and positioned normally above said main table to hold the rearward portions of sheets passed 115 over said auxiliary table in raised position above said main table so as not to interfere with the feeding of sheets over said main table, said auxiliary table being swingable to lowered position, so that the sheets operating thereover may be more easily inserted around said platen, and means for limiting the downward movement of said auxiliary table, said means comprising a rod fixed to said platen-frame, and a stop carried by said auxiliary table and engaging said rod 120 in the lowered position of the auxiliary table, said means comprising a rod fixed to said platen-frame, and a stop carried by said auxiliary table and engaging said rod 125 in the lowered position of the auxiliary table.

11. In a typewriting machine, in combination, a revoluble platen, a platen-frame comprising a rear paper-table, an auxiliary table above the rear paper-table and having its lower edge adjacent the rear of the platen, and means for supporting said auxiliary table for movement to a lower position adjacent said rear paper-table and with its lower edge comparatively close to the apex of the opening between the rear paper-table and the rear of the platen for insertion of a work-sheet above the auxiliary table, or to an upper position with its lower edge withdrawn rearwardly for insertion of a second work-sheet over the rear paper-table and around the platen outside of the first work-sheet.

12. In a typewriting machine, in combination, a platen-frame comprising a rear

paper-table, a platen journaled in said frame, and an auxiliary table to support above said rear paper-table a work-sheet and a carbon-sheet having an extension beyond the trailing edge of the work-sheet, so that a second work-sheet may be inserted over the rear paper-table, the forward edge of said auxiliary table being sufficiently close to the apex of the opening between the rear paper-table and the platen to enable the extension of the carbon-sheet to support the rear edge of the first work-sheet, when the latter is drawn off the auxiliary table, and to guide the second work-sheet around the platen outside of the first.

JESSE A. B. SMITH.
